GUNRACK

Leo C. Smith, 2958 Arrowhead Drive,
Abilene, Tex. 79606

Continuation-in-part of design application Ser. No.
4,697, Nov. 16, 1966. This application Aug. 2,
1967, Ser. No. 8,102

Term of patent 14 years

(Cl. D33—3)

FIG. 5.

FIG. 6.

FIG. 7.

FIGURE 1 is a perspective view showing my new design for a gunrack;

FIGURE 2 is a top plan view thereof;

FIGURE 3 is a side elevational view thereof, the other side being its mirror image;

FIGURE 4 is a bottom plan view thereof;

FIGURE 5 is a perspective view showing a modification of my new design for a gunrack;

FIGURE 6 is a top plan view thereof; and

FIGURE 7 is a bottom plan view thereof.

This is a continuation-in-part of design application Ser. No. D4697, filed Nov. 16, 1966, and now abandoned. I claim:

The ornamental design for a gunrack, substantially as shown and described.
